Application June 25, 1947, Serial No. 756,839

15 Claims. (Cl. 128—203)

1 This invention relates to artificial breathing devices, and more particularly to resuscitators, inhalators, and the like.

In the past, devices for artificially inducing, aiding or promoting breathing that have been used, in some instances comprise artificial respiration devices for alternately forcing air or oxygen into the lungs and for applying suction to withdraw gases from the lungs. Devices have also been provided for supplying oxygen or other gas to a patient at a constant rate.

These prior artificial respiration devices, while useful in many cases, failed to meet fully all the requirements and in some instances caused damage to the patient, as by forcing gases into and out of the lungs too rapidly, or at too great a pressure, and thereby causing injury to the lungs or other parts of the respiratory system. In some instances, devices adapted to supply gases at a predetermined speed of respiration, or at a given pressure and in a certain percentage mixture were suitable for some patients but not for others with different requirements.

Means are provided by the present invention for overcoming these various disadvantages and providing other improvements in such devices. In its preferred embodiment, the invention contemplates a device capable of administering a gas, such as oxygen, and air in mixtures, the proportions of which can be adjusted or varied at will by the operator, and the pressures of which gases can likewise be controlled and adjusted. A device in accordance with the present invention may also provide for adjusting the speed of respiration. It may also provide safety means to prevent damaging gas pressures being administered. The invention also contemplates improvements in specific features and parts of gas administering devices, such as valves, pressure regulating members, metering devices, gas mixing means, control elements and the like.

An object of the invention is to improve artificial breathing devices and apparatus, and devices for producing artificial respiration. Another object is to improve devices for administering oxygen or other gases to a human being or animal with the application of pressure variations or alternations to induce artificial respiration to induce or promote breathing. A further object is to improve devices for administering oxygen or other gases under constant or substantially constant flow to a patient or subject to facilitate breathing or for other purposes.

A further object is to provide a device for use in aiding human beings or animals in instances

where breathing is hindered or requires artificial aid or stimulation, such as in cases of asphyxia caused by accident, sickness, drowning, gas asphyxiation, poliomyelitis, or the like. A still further object is to provide a device adapted for use in artificial respiration and also adapted for use to supply a relatively constant flow of oxygen or gas to a patient.

Another object is to provide an oxygen or gas 10 administering device having means for mixing a gas being administered with another gas, such as air, and for varying or adjusting the proportions of each. A further object is to provide a device of the kind described having means for 15 varying or adjusting the pressures of gas, air or gas and air being administered. Still another object is to provide a device for inducing artificial respiration and for adjusting or varying the rate or periodicity of such respiration. An additional 20 object is to provide a gas administering device having means for varying the percentages of gases in a gas mixture, the pressure of the gases being administered, the speed of respiration or any combination of these by adjustable means 25 under control of an operator.

Another object is to improve artificial breathing and gas administering devices and the parts thereof, such as valves, pressure regulating members, metering devices, gas mixing jets and chambers, control elements, and other parts.

Other objects of the invention will be apparent 30 from the following description and accompanying drawings taken in connection with the appended claims.

The invention accordingly consists in the features of construction, combination of elements, and arrangement of parts as will be exemplified in the structures to be hereinafter described and 40 the scope of the application of which will be indicated in the following claims.

While a preferred embodiment of the invention is described herein, it is contemplated that considerable variation may be made in the method of 45 procedure and the construction of parts without departing from the spirit of the invention. In the following description and in the claims, parts will be identified by specific names for convenience, but they are intended to be as generic in their application to similar parts as the art will permit.

In the accompanying drawings in which are shown by way of illustration several possible embodiments of my invention:

Figure 12 is a vertical section taken along the line 12—12 of Figure 3;

Figure 13 is a fragmentary view of the oxygen percentage metering valve control with speed control in shut off position;

Figure 14 is a similar view with metering valve percent control set at 100% and the breathing speed control set at fast;

Figure 15 is a partial cross section through a portion of Fig. 2 with portions cut away to other planes to show with clarity the arrangement of passages leading to the venturi and to the various valves;

Figure 16 is a vertical cross section taken on the line 16—16 of Figure 19 showing the front of the back plates to show parts (M, N, O, G);

Figure 17 is an enlarged fragmentary section of one of the jets and jet caps, taken on the line 17—17 of Figure 18;

Figure 18 is a top plan view of the Venturi unit, partly in section and partly in elevation, taken approximately on the line 18—18 of Figure 5;

Figure 19 is a horizontal section of the Venturi unit taken on line 19—19 in Figure 16 or 20;

Figure 20 is a vertical cross section of the Venturi unit taken on the line 20—20 of Figure 19, the jet and the jet caps being shown diagrammatically for clearance; and

Figure 21 is a horizontal section taken on the line 21—21 of Figure 18, showing the safety valve assembly.

Referring to the drawings in which a preferred embodiment of the invention is shown, Figure 1 diagrammatically illustrates the arrangement of the gas passages in connection with which the flow of gases through the device will first be described briefly. Preparatory to use, tanks 30 and 38 of compressed oxygen are attached to the device and the valve 31 of tank 30 is opened. Gas pressure will thus be supplied through check valve 32, branch 33 of gas supply passage 34 to pressure indicating gauge 35 and to pressure regulator 36. Gas passing through the regulator builds up pressure in supply passage 37. Shut-off valve

38 (shown in open position) at the end of passage 37 is kept closed until the device is put into operation. However, gas can be released by opening the cap of normally-closed auxiliary gas outlet 39 if desired for testing, relieving the pressure or other purposes.

Oxygen tank 30 is provided as a reserve supply source and its valve 131 will normally be kept closed until tank 30 is exhausted, at which time, valve 131 will be opened to continue the oxygen supply without interruption. Check valves 32 and 132 in branch passages 33 and 133 permit entrance of gas from the tanks into passage 34 but prevent escape of gas through either branch in case of a leaky coupling to either supply tank and during removal of either of the tanks for replacement while the gas supply is continued from the remaining tank.

When it is desired to put the device into use to produce artificial respiration the oxygen mask 40, connected by hoses 41 and 42 to the device, is fitted over the nose and mouth of the patient and shut-off valve 38 is opened.

Respiration cycle—Negative phase

Figure 1 shows the valves in the position they will occupy during the negative phase of the artificial respiration cycle, when gas is being withdrawn from the lungs of the patient. Oxygen from tank 30 is supplied through passages 33 and 34, pressure regulator 36, passage 37, open shut-off valve 38 and passage 43 to distributing valve 44. This valve can alternate between two positions to supply the oxygen from passage 43 to a "negative phase" jet 45 or a "positive phase" jet 46 for projecting the gas alternately into the two ends of a venturi 47. During the negative phase the valve is open to passage 48 leading to jet 45 and closed to passage 49 leading to jet 46. The gas, projected from jet 45 into venturi 47 at high speed, creates a partial vacuum in chamber 53 which surrounds jet 45. This partial vacuum draws gas from the lungs of the patient through hose 41, patient's check valve 51, equalizing chamber 50, passage 53 and speed control valve 56. Simultaneously, the partial vacuum withdraws gas through passage 52 from diaphragm chamber 57 behind control diaphragm 58. The gas from jet 45, together with the gas drawn from the patient and from chamber 57 through valve 56, is expelled through venturi 47 into chamber 54 surrounding jet 46 and escapes to the atmosphere through vent 61 in the wall of chamber 54. Diaphragm 58 is drawn gradually inward at a rate determined by the pressure in connected chambers 57 and 58, bending resilient lever 60 to apply a force tending to shift distributing valve 44 from the position shown in Figure 1 to the opposite position. As soon as this force becomes sufficient to open the valve seat leading to "positive" jet 46 the valve snaps over to close passage 48 leading to "negative" jet 45.

Positive phase

Transfer of valve 44 starts the positive phase in which oxygen from jet 46 passes through venturi 47 increasing the pressure in chamber 53 sufficiently to reverse the gas flow through valve 56 and supply gas to the patient through passage 53, chamber 50, check valve 52 and hose 42. Oxygen from jet 46 passing through the venturi carries with it a certain proportion of gas from chamber 54. The composition of this gas is determined by the setting of percentage metering valve 62 which admits oxygen to chamber 54

from passage 49. This mixes with air entering through vent 61 and also determines the rate at which such air enters the chamber to provide a predetermined oxygen-air mixture.

During the positive phase some of the gas from chamber 53 flows back through passage 59 into diaphragm chamber 57 moving diaphragm 58 outward preparatory to shifting of distributing valve 44 back to the first position to repeat the cycle.

Steady flow

When it is desired to supply a steady stream of oxygen or other gas or of a gas-air mixture to the patient, diaphragm 58 is moved to its innermost position by turning control lever 62 pivoted to yoke 64. This locks distributing valve 44 in a position to close passage 48 so that positive jet 46 operates steadily to drive gas or gas mixture through venturi 47, valve 56, passage 55, chamber 59, check valve 52 and hose 42 to the patient.

Mechanical construction

The structural features of a resuscitator and inhalator device having the gas flow system and operating as diagrammatically shown in Fig. 1 are illustrated in Figs. 2-21 and comprise a preferred embodiment of the invention. These figures comprise illustrative embodiments of the complete machine, portions thereof and of various parts.

As viewed in Fig. 2, the resuscitator has a back plate cover unit 65 which is formed to provide the back of a chamber 57. (Chamber 57 is closed at the front by a flexible diaphragm 58, see Figs. 3 and 4.) Bolted or attached in other suitable manner to the base of 65 and extending forward from it is casting 66 (see Figs. 3, 4, and 5) which has sides of generally rectangular configuration. Casting 66 is hollowed out and bored to provide space for venturi 47, its associated valves and various gas passages associated therewith all of which will be described in more detail hereinbelow. Pressure regulator 35 (see Fig. 2) of any suitable design is bolted or otherwise suitably attached to the top and front of casting 66 and is in front of diaphragm 58. A pair of gas tank yoke members 67 and 167 are fitted to threaded coupling nipples 68 and 168 and project out laterally from the edges of pressure regulator 35 and may be integral parts of its housing casting 80 (see Figs. 3 and 4). Gas tanks 30 and 130 have their valve heads 31 and 131 clamped in yokes 67 and 167 by clamp screws 69 and 169 respectively. A yoke-shaped carrying handle 70 is screwed onto the back of yokes 67 and 167 and back plate 65 may have a pair of ears (not shown) clamped between the arms of handle 70 and yokes 67 and 167. A hollow casting 73 preferably having a beveled front face (see Figs. 2, 5 and 19) is bolted or otherwise suitably attached to casting 66. Equalizing chamber 59 having valves 51 and 52 with hose-attaching nipples 71 and 72 (see Fig. 19) attached thereto is formed in casting 73. Casting 73 also carries auxiliary gas outlet nipple 39 and valve 38.

As may be readily seen in Fig. 2, immediately above casting 73 is attached a front plate casting 74 carrying curved dial plate 184 having indicating scales for the percentage metering valve control handle 75 and selector control handle 76 whose function will be described later. Speed control lever 77 is pivoted in front plate casting 74 above dial plate 184. Pressure gauge dial window 262 is mounted in a circular opening of front

plate 74 and an extension 78 of plate 74 bridges the space between the top edge of the pressure gauge and the top edge of back plate cover unit 65. Left and right sides plates 79 and 179 are screwed or clamped to the sides to complete the housing.

Pressure regulator 35 may be of a conventional construction. It is seen most clearly in sectional view in Fig. 5 and in rear view in Fig. 12.

- 10 It comprises a housing casting 80 with which nipples 68 and 168 are integral and has a hollow support stem 81 clamped and sealed to a recess in the top face of casting 66 by bolt 82 passing upward through casting 66. A flexible diaphragm 83 made of thin metal is clamped over the back face of casting 80 closing its hollow interior. Gas pressure duct 34 connected to oxygen inlet passages 33 and 133 is bored or otherwise formed within casting 80 and terminates in a jet nozzle 34 directed away from diaphragm 83. A valve seat 85 carried by yoke 86 secured to the center of diaphragm 83 is disposed in front of nozzle 34 to close or partly close it when yoke 86 is pulled back by diaphragm 83
- 15 as a result of increased pressure in the hollow interior of regulator 35. An adjustable spring bar 87 is clamped at one end against the outside of diaphragm 83 by clamp 263 (see Fig. 12). Adjusting nut 264 enables setting of the regulator to supply a predetermined gas pressure to
- 20 regulator outlet gas supply passage 37 leading through support stem 81 and casting 66 to shut-off valve 38 and auxiliary gas outlet nipple 39. Gas outlet nipple 39 is provided with a closure cap 88.

- 25 The internal structure of oxygen inlet check valve 32 is shown in Fig. 6 with the valve closed to prevent escape of gas and in Fig. 7 with the valve open to allow gas to enter branch passage 33 formed in nipple 68 from a gas tank clamped to the device. Valve 32 comprises an externally-threaded metal shell screwed into the end of nipple 68 (see Fig. 2) and having a hexagonal flange which seats against the outer end of the nipple. It also has (see Figs. 6 and 7) a small outwardly projecting tube 90 around which is fitted a washer 91 of fibre or rubber (see Fig. 2) against which is seated the valve outlet of gas tank 30. The bore of tube 90 extends axially into the valve where it joins the larger cylindrical interior passage 88 of the valve. A cylindrical core 92 molded of a pliable material such as rubber, synthetic rubber, or a resilient plastic, fits loosely within passage 88. Core 92 is molded to provide a generally cylindrical body portion terminating at the inner end in a cylindrical flange 93 preferably molded so as to have a tendency to flare out at the inner end as shown in Fig. 6. A central boss 94 comprises part of core 92 extending inwardly inside of flange 93 carries a headed pin or screw 95 molded into the body of the core or screwed into it. The head of pin 95 is provided with notches 96 so that when the core is moved inward to bring the head of pin 95 against the conically tapered wall 97 leading to branch passage 33 in nipple 68, the head of pin 95 will not obstruct entry of gas into branch passage 33. A headed screw 98 is screwed into the other end of core 92 and has a head the same diameter as the core. This head is also provided with slots or notches 99 so that when the head is seated in the bottom of passage 88 it will still permit the passage of gas from tube 90 into the valve.
- 30 Check valve 32 effectively prevents gas from
- 35
- 40
- 45
- 50
- 55
- 60
- 65
- 70
- 75

escaping from the system through tube 90 by sealing the passage. Fig. 6 shows the valve in closed or sealed position. It will be noted that flange 93 is pressed tightly against cylindrical wall of passage 88 completely blocking off the passage. Fig. 7 shows valve 32 in the position it will occupy when gas is being supplied to the system from a gas tank 30 attached over projecting tube 90. In this instance, the core 92 is shifted inward sufficiently to permit gas entering through tube 90 to pass around the head 93 and along the sides of core 92, which is slightly smaller in diameter than passage 88 and into branch passage 33 of the regulator. Notches 93 aid in providing an open passage at this time. Flange 93 is moved inward to substantially the cylindrical position shown in Fig. 7 by the pressure of the gas in tank 30.

The construction of check valve 132 (see Fig. 4) connecting gas cylinder 120 to passage 33 is similar in construction to check valve 32 and the description need not be repeated here.

The construction of shut-off valve 38 is formed by boring or otherwise forming a cylindrical recess 38a in casting 66 which extends downwardly from the top face of casting 66 as shown more clearly in Figs. 5 and 15. In forming this valve, a hole 43a smaller in diameter than recess 38a is countersunk in the bottom of that recess. Hole 43a is provided with an annular ridge 101 formed around its mouth. Recess 43a forms a part of gas passage 43 (see Fig. 1). Passage 43 continues horizontally and backward (as shown at 43b in Fig. 15) in casting 66 and connects with recess 100 in that casting which houses distributing valve 44 (see Figs. 15 and 19). Returning to consideration of Fig. 5, a floating washer 102 made of any suitable material which is pliable such as fibre, leather or rubber, is fitted into the valve recess 38a. Washer 102 normally rests on annular ridge 101. Above washer 102 is a valve head 103 which is also provided with an annular ridge 104 concentric with and substantially the same diameter as ridge 101. Valve head 103 and washer 102 are substantially rectangular in shape but have rounded corners which fit against and thus form bearing surfaces against the wall of recess 38a. Valve head 103 is supported on a stem section 105 which may be made integral with it. Stem section 105 is threaded to another section 106 and the two sections clamp between them the center edge of an annular flexible diaphragm 107. The outer edge of diaphragm 107 is clamped against the face of annular step 108, formed at the mouth of valve recess 38a, by clamping ring 109 which is held in place in casting 66 by screws 110. The upper end of upper stem section 106 is provided with a head 111 of increased diameter by which a helical compression spring 112 is compressed between head 111 and clamping ring 109. Compression spring 112 thereby urges valve head 103 upwardly and away from its seat against washer 102 to open the valve. The valve is closed by rotating speed control lever 77 which brings set screw 113 mounted on bracket 208 attached to lever 77 down against head 111 to move valve head 103 to its closed position against its seat formed by washer 102.

Distributing valve 44 is housed in a cylindrical recess 106 bored or otherwise formed at the rear end of casting 66. As may be seen most clearly in Figs. 5 and 15, recess 100 is closed at one end with valve seat plate 114. Valve seat plate 114 has an annular ridge 115 surrounding a circular

hole 114a in plate 114. This hole continues into a passage 48a of decreased diameter bored in the lower part of back plate unit 65 and forms part of passage 49. The rest of passage 49 is made up of vertical section 49b in back plate unit 65 and passage 49c formed within back plate unit 65 and casting 66. Portion 49c connects vertical portion 49b with positive jet 46 of venturi 47 through vertical portion 49d (as shown in Figs. 15 and 20). Portion 49c of passage 49 continues beyond vertical portion 49d and terminates in percentage metering valve 62. A sealing gasket 116 of any suitable material is clamped between the rear of casting 66 and the lower portion of the inside face of back plate unit 65 and is provided with suitable apertures for the respective gas passages 49a and 49c.

At the end of recess 100, opposite that at which valve seat plate 114 is located there is bored in casting 66 a recess 48a of smaller diameter than recess 100. An annular ridge 117 is formed around the entrance into recess 48a from recess 100.

Recess 48a comprises part of gas passage 48 leading to negative jet 45 of venturi 47. The rest of passage 48 is clearly shown in Figs. 5, 15, 19 and 20 and comprises a horizontal portion 48b and a vertical portion 48c terminating in jet 45 as shown in Fig. 20.

A pair of floating washers 118 and 119 are normally seated against annular ridges 115 and 117 respectively in recess 100. A sliding valve head 120 is mounted in recess 100 to slide back and forth between washers 118 and 119. The structure of valve head 120 which can be seen most clearly by reference to Figs. 5 and 5a, comprises a single metal part having a pair of ends 121 and 122 carrying annular ridges to cooperate with washers 118 and 119 respectively. Valve head 120 is generally rectangular in shape but is cut off at its four corners to provide bearing faces 123 (see Fig. 5a), which slide on the cylindrical wall of recess 100 thereby guiding and centering the valve in the recess. Washers 118 and 119 are of similar modified rectangular shape. Between valve head ends 121 and 122 a pair of recesses 124 and 125 extend into valve head 120 from its top and bottom faces. These are joined by central opening 126 of smaller diameter than the recesses. The lower end of valve control lever 60 fits loosely in opening 126.

A valve control lever 60 extends upwardly through an opening 127 bored or otherwise formed in casting 66. Plug 128 is screwed into the top of opening 127 which is suitably threaded for that purpose. Plug 128 has a central opening 129 through which lever 60 extends. Lever 60 is provided with a collar or enlarged portion 134 which bears against washer 135 seated against the lower end of plug 128. The central opening 129 is of sufficient diameter to allow control lever 60 to move freely in all directions. Thus the collar or enlarged portion 134 of control lever 60 pivots that lever at the lower end of plug 128. Plug 128 has a short extension 137 projecting upward from its main portion. A tapered helical spring 136 surrounds the portion of control lever 60 extending above plug 128 and is welded or otherwise attached to control lever 60 at its upper end. The lower end of spring 136 surrounds extension 137 of plug 128 and rests against the shoulder formed thereon. Spring 136 is in compression thereby tending to hold collar or enlarged portion 134 of control lever 60 against washer 135. Furthermore spring 136 is biased to

hold the upper end of control lever 60 in one of its two extreme positions with the result that valve head 120 will always be in one of its extreme positions and will positively close either passage 49a or passage 48a. Thus it is not possible for valve head 120 to come to rest at an intermediate position. Spring 136 may be given a bias from its true vertical position so that it holds the top of control lever 60 normally in its rear position and in turn holds valve head 120 in its forward position and closes passage 48. This assures that when the device is first put into operation it will start with the positive phase of the respiration cycle.

The forward and backward motion of control lever 60 is controlled by the motion and position of diaphragm 58. This is accomplished by means of a U-shaped yoke member 145 having two arms 147 and 148 which engage the end of control lever 60. Yoke 145 is suitably connected to diaphragm 58 by pin 143 to which yoke member 145 is attached by screw 146 and which in turn is securely attached to diaphragm 58 by nut 144 passing through circular plates 140 and 141 clamped to the inner edge of diaphragm 58. It is thus seen that any movement of diaphragm 58 is transmitted to control lever 60 and valve head 120 and in turn, as may be seen from Fig. 19, the flow of gas to positive jet 46 and negative jet 45 and venturi 47 is controlled.

When the device is operating, the gas pressure in distributing valve chamber 100 will hold valve head 120 in a position where either passage 48a or 49a is closed. Valve head 120 will not be accidentally opened due to jarring. The pressure in chamber 100 will impose sufficient opposition to the movement of valve head 120 so that control lever 60 will bend slightly before valve head 120 will move thus insuring that when valve head 120 moves it will quickly snap over to its other position. When the respirator is set to supply minimum gas pressure to the patient, the gas pressure in chamber 100 opposing valve head 120 constitutes the principal load on diaphragm 58 and hence determines the gas pressure in chamber 50 in front of diaphragm 58 and chamber 57 behind diaphragm 58 at which the change over from positive to negative phase takes place.

The adjustment of gas pressure regulator 36 by changing the setting of screw 264 (see Fig. 12) which changes the position of clamping spring bar 87 against pressure diaphragm 83 changes the gas pressure supplied to valve chamber 100. By this the pressure of the gas mixture supplied to the patient at the minimum pressure setting can be adjusted to any desired value. While this adjustment can be used as the sole means of varying the pressure supplied to the patient, it is more convenient to pre-set the pressure regulator for the minimum gas pressure which the respirator will ever be required to deliver and provide a further means to supply higher positive and negative pressures by imposing a spring load on diaphragm 58. This spring load operates through yoke member 64 (see Fig. 5) riveted by rivet 150 at its midportion to the middle of plates 140 and 141 which are clamped to the middle of diaphragm 58. The two arms 151 and 152 (see Fig. 9) of yoke 64 extend around the two sides of pressure regulator 36 and are pivoted at their forward ends to a pair of arms 153 and 154 respectively on a lever piece 63 (see Figs. 9, 10 and 11) by pivot screws 156 and 157.

The response of diaphragm 58 to positive and negative pressures is controlled by adjusting the force of a spring 160 acting through lever mem-

bers 161 and 63 in a manner which can be most clearly seen by reference to Figs. 5, 9, 10 and 11. Lever 161 is pivoted at its upper end on a pin, such as a cotter pin 162, passing through a pair of flanges 163 comprising part of front plate casting 74 forming part of the housing. Lever 161 extends generally downward from pivot 162 and is provided at its lower end with a pair of spaced fingers 164 (see Fig. 9) straddling the shank of an adjustable screw 165 screwed into casting 74. Spring 160 is a helical compression spring which is seated against a screw plug 166 (see Figs. 10 and 11) in threaded passage 196 extending through the mid-portion of casting 74. The other end of spring 160 carries a rivet-like bearing member 167 having a conically pointed head which rests in a tapered recess 169 formed in the front face of lever 161 near its pivoted upper end. Thus, spring 160 is held in compression between the upper portion of lever 161 and the front plate casting 74. The lower part of lever 161 is arched forward to provide a substantially half-round channel 171 extending across its rear face to permit the lever to partially surround the pivot portion of lever 63. Lever 161 has a pair of transverse bearing portions or ridges 155 and 170 at the upper and lower edges of channel 171 for engagement with lever 63. Lever 63 is pivoted by roller bearings 172 on eccentric cam 173 on shaft 174 which is in turn pivoted in a pair of spaced flanges 175 extending back from front plate casting 74. Lever 63 has a bearing face 149 above the pivot, which face is engaged by ridge 155. The lower end of lever 63 extends below the pivot to provide a bearing surface 176 which engages ridge 170 on lever 161. Shaft 174 is coupled to control arm 177 (see Figs. 4 and 9) to which selector handle 76 is attached. Arm 177 is directly attached to shaft 174 and is formed with a circular segment 178 (see Fig. 4) which is disposed directly inside the wall of front plate casting 74, which is curved forward behind dial plate 184 to provide a rounded hollow 199.

Referring to Fig. 4, segment 178 carries a friction spring 180 comprising a short length of spring wire clamped on one end of segment 178 in a socket 181, the free end of spring 180 extends generally parallel to segment 178 and is biased to press against the inside of rounded hollow 199 of casting 74 to form a friction bearing. It thereby holds lever 177 in any setting given to it by adjustment of selector handle 76. The free end of spring 180 is turned in as shown at 182 so that a rounded surface of spring 180 engages segment 199.

Still referring to Fig. 4, selector handle 76 is screw threaded into lever 177 and is knurled or otherwise neatly formed into a suitable handle and carries a pointer 183 (see Fig. 2) which may be secured underneath the head of the handle. Dial plate 184 comprises a slotted sheet metal plate provided with two vertical slots 188 and 209, alongside which are suitable dial markings. Dial plate 184 is bent into a quarter-round shape and is attached over the front of rounded part 199 of casting 74 by screws 185 to provide an indicating dial for the device.

Referring to Fig. 4, steady-flow holding lever 186 comprising a substantially straight piece of metal strip is pivoted on the right hand end of shaft 174 and extends upwardly to a position between pivot screw 157 on the end of lever arm 154 of lever piece 63 and the socket 181 at the upper edge of segment 178 on arm 177. The me-

11

tallic strip forming lever 186 is twisted through a right angle at its mid-portion so that the lower pivoted end lies flat against the end of shaft 174 (as shown in Fig. 9) where it is held by set screw 187 and the upper end of the arm is in a plane extending across the device (through the sheet of paper as shown in Fig. 4) thus, forming a greater bearing area for engagement with screw 151 and socket member 181. Lever 186 is pivoted to float freely on shaft 174 and normally rests at its upper end against the inside face of front plate 74. However, if lever 177 is rotated in a clockwise direction (as viewed in Fig. 4 or upward in Fig. 2) until selector handle 76 and its associated pointer 183 reach their uppermost or "Steady flow" position as defined by slot 188 in dial plate 184 through which the shank of selector handle 76 extends, then the upper end of socket 181 will engage lever 186 and force it firmly against pivot screw 151 to positively force yoke 64 backward and diaphragm 58 to its rear-most position. As seen by Fig. 5 with this setting lever 60 is moved into the position so that distributing valve head 120 is held in forward position closing the passage 48 leading to negative jet 45 and holding passage 49 leading to positive jet 46 open to permit a constant flow of gas to positive jet 45 and to percentage metering valve 62. It is seen that a steady supply of gas or gas and air mixture is furnished through passage 49, speed control valve 56, passage 55, chamber 50 (for all of which see Figs. 1 and 15), check-valve 52, passage 72 (for both of which see Figs. 1 and 19) and through any suitable device such as a hose 42 (see Fig. 1) to the patient. Since diaphragm 58 is clamped in rear position by lever 166 the gas pressure in chambers 50 and 57 is insufficient to move diaphragm 58 forward and hence positive gas supplied to the patient remains constant as long as selector handle 76 is left at the top setting indicated by the legend "Steady flow" on dial plate 184 near the top of slot 188. The relationship of levers 63 and 161 at this time will be substantially as shown in full lines in Fig. 11.

When it is desired to use the device as a resuscitator, instead of as a steady-flow device, selector handle 76 is moved downward. Assuming the patient is an adult requiring the full capacity of the device, handle 76 (see Fig. 2) will be moved to the bottom of slot 188 so that pointer 183 stands over the legend "Adult" on the dial plate. Reference to Figs. 10 and 11 shows that since bearing part 173 is eccentrically mounted on shaft 174 part 173 is moved forward from the position shown in Fig. 11 to the position shown in Fig. 10 as shaft 174 is rotated by movement of handle 76. At the same time lever 186 is released since socket member 181 is dropped as is clear from Fig. 4. This places diaphragm 58 under control of compression spring 160 acting through levers 181 and 63. It will be noted by viewing Figs. 10 and 11 that compression spring 160 tends to rotate lever 161 in counter-clockwise direction to bring it against the head of set screw 165.

When diaphragm 58 is drawn backward toward the rear end of its stroke, thereby drawing the top of lever 63 backward (to the right as shown in Fig. 11), spring 160, acting through ridge 170 on lever 161 and bearing surface 176 on lever 63 will tend to rotate lever 63 in a counterclockwise direction, as indicated by the full lines in Fig. 10, thereby opposing the inward pull on the diaphragm caused by the partial vacuum in chamber 57. This makes it necessary for a greater

12

vacuum (or negative pressure) to develop in chamber 50 before a negative phase of a cycle can end and hence applies a greater pull (or negative pressure) to the patient than would be applied if spring 160 was not in use.

During the positive pressure phase of the respiration cycle diaphragm 58 will move forward thereby rotating the upper end of lever 63 forward to a position such as is indicated by dotted lines in Fig. 10. In this position ridge 155 will engage lever face 149 to oppose the forward pressure and hence will make it necessary for a greater pressure to build up in chambers 57 and 50 before valve 44 is tripped. This applies the maximum gas pressure to the patient.

It will be noted that the length of lever 161 between pivot pin 162 and ridge 170 is substantially twice the distance from the pivot 162 to ridge 155. As a consequence the resultant spring pressure acting through lever 161 tending to rotate lever 63 forward during the negative phase is substantially one half the resultant spring pressure applied to lever 63 and tending to rotate it backward during the positive phase. In other words, the ratio of the gas pressures applied to the patient is determined by the distance from the pivot 162 of the two ridges 155 and 170 and, in the embodiment illustrated, the ratio between positive and negative pressures is substantially 2 to 1. It is obvious that should other ratios be desired they can be provided by replacing lever 161 as shown with a lever of the same general construction but having the ratio of the distance from pivot 162 to ridge 170 to the distance from pivot 162 to ridge 155 such that the desired ratio of pressure is obtained. By positive pressure is meant the excess of the pressure in chambers 50 and 57 over atmospheric pressure and by negative pressure the amount by which the pressure in these chambers falls below atmospheric.

It will be apparent from Figs. 10 and 11 that during each forward stroke of diaphragm 58, lever 63 will pass through an intermediate transfer position or zone in which bearing face 149 will come into contact with ridge 155 thereby lifting ridge 170 off bearing face 176. A reverse transfer takes place on the backward stroke. With the setting of eccentric 173 shown in Fig. 10, transfer may take place without lever 161 swinging to the right enough to engage the head of screw 165. Thus, a spring load is always applied to diaphragm 58 tending to resist movement away from its intermediate rest position. As spring 160 becomes more compressed near the ends of the stroke the resistance increases up to the point where valve 44 is shifted after which the spring rapidly returns the diaphragm to intermediate position and then opposes the movement of the diaphragm for the rest of the stroke. With control handle 76 set at its lowest position the effect of spring 160 in opposing diaphragm movement will be at the maximum.

If the patient is a child, newborn infant, or an individual requiring only a small amount of breathing assistance, it is desirable to apply artificial respiration at positive and negative gas pressures which are less than the adult maximum. For this purpose handle 76 can be set at an intermediate position, for example, in position marked 70 with the legend "New born" or "Assistor" on dial plate 184 (Fig. 1) or any other intermediate setting. Referring again to Figs. 10 and 11 this will rotate eccentric 173 to a position somewhere between those shown in those two figures. The result is that the pivot point of lever 63 is moved to

the rear of the position shown in Fig. 10 which will permit lever 63 and diaphragm 58 to go to the ends of their forward and backward strokes without compressing spring 160 to such a great extent as if handle 76 were in the "Adult" position. Thus, both the positive and negative pressures applied to the patient will be reduced proportionally by simply changing the setting of handle 76. By choosing a spring 250 having sufficiently great tension, the device can be adjusted to supply only positive pressures in the "Assistor" position, if desired. Spring 250 as is shown in Fig. 4 is attached at one end to pivot screw 157 and anchored at its other end to casting 66 on lug 261 at its other end.

Referring to Figs. 10 and 11 set screw 165 can be adjusted to bring its head to the desired position to take the spring load off lever 63 during a shorter or longer part of the intermediate portion of its stroke. It may preferably be set so that the spring is not in use at the top setting of handle 76, the position shown in Fig. 11, but comes into use through progressively greater portions of the stroke as handle 76 is moved to lower settings on the dial until the spring is in use throughout the stroke when handle 76 is at the lowest setting, the position shown in Fig. 10.

Spring 250 is a relatively light spring to hold diaphragm 58 in its rear position and to insure that distributing valve 44 will be set for the positive phase of the cycle when the machine is at rest. In order to compensate for the added spring load opposing the shifting of the valve head 120 from this setting, the annular ridge 117 of valve 44 (see Fig. 5) is made slightly smaller in diameter than ridge 115 so that the gas pressure in valve 44 tending to hold the valve closed against passage 48 will be slightly less than that tending to hold the valve against passage 49 on the opposite phase.

As shown in Figs. 2, 3, and 4 speed control lever 77 comprises a crank lever having a handle 189 for manual operation, the lever is secured to a shaft 190 which extends through the upper part of front casting 74 in a front-to-rear direction and terminates in an eccentric sheave 191 which is shown in detail in Figs. 5, 8 and 9. Speed control cross head 192 has a central upstanding arm 193 provided with a transverse cam slot 194 engaging sheave 191. Slot 194 is cut in from the left hand edge of arm 193 as viewed in Fig. 9 and has a rounded closed end 195 to the right of sheave 191. The lower end of arm 193 is joined to the middle of a transverse arm 200 and may be integral therewith. Cross head arm 200 carries on one end a needle valve pin 201 comprising part of speed control valve 56 located as shown in Fig. 8 in chamber 63. Pin 201 extends down through passage 202 bored in casting 66 and terminates in a tapered point 203 adapted to seat in the mouth of passage 55a bored in casting 66 thereby forming valve 56. Passage 55a joins passage 55b leading to chamber 59, these passages together correspond to passage 55 of Fig. 1. A gas seal is provided around pin 201 at the top of hole 202 by packing gland 204.

The other end of cross head arm 200 carries a guide pin 205 (Figs. 3 and 8) which slides in a vertical guide hole 206 in casting 66. Cross head arm 200 carries a flange 207 on the rear edge of its mid-portion provided with a threaded opening in which is mounted a set screw 113 held by lock nut 208. The lower end of screw 113 is disposed directly over head 111 on valve stem 106 comprising part of shut-off valve 38 (see Fig. 5).

Speed control lever 77 controls the rate of gas supplied to the patient as well as the rate of respiration. When lever 77 is turned to the right as viewed in Fig. 2 so that its arm is adjacent to legend "Fast" on front plate 74, eccentric sheave 191 is moved to its uppermost position and thereby raises web 193 and cross head 192 to open valve 56 to its widest-open position as shown in Fig. 8. If it is desired to lower the rate of gas supplied and the rate of respiration, lever 77 is rotated in a counter-clockwise direction as viewed in Fig. 2 to an intermediate position. Thus, if the slowest rate is desired it is moved to bring lever 77 over the legend "Slow" on front plate 74, thereby almost closing valve 56. If it is desired to cut off the gas supply entirely and thereby stop the operation of the device, the lever is moved still further in a counter-clockwise direction to the position marked "Off" on the front plate, thus completely closing valve 56. This final motion also moves set screw 113 (see Fig. 5) down against head 111 of valve 38 to force valve head 103 against washer 102 and thereby shut-off the gas supply to the distributing valve 44 and the Venturi jets.

Should the gas supply not be shut off by valve 38 at the same time that valve 56 is closed (for instance, as a result of improper setting of set screw 113) no harm will come to the device since the gas supplied to the Venturi jet will escape to the atmosphere through vent 61 as shown in Fig. 15.

Percentage metering valve 62 shown diagrammatically in Fig. 3 and in detail in Figs. 13 and 14 is controlled by metering valve handle 75 through a lever arrangement. The shank of control handle 75 extends through slot 209, see Fig. 2) near the left hand edge of dial plate 184 parallel to slot 198. Handle 75 is also provided with a pointer 210 cooperating with a series of numeral legends on the dial plate alongside slot 209 indicating various oxygen or gas percentages. Referring again to Figs. 13 and 14, the shank of handle 75 is screwed into a segment shaped lever 211 pivoted on the left hand end of shaft 174. Segment lever 211 carries a socket 212 in which is received the end of friction spring 213 (see Fig. 3) arranged similarly to friction spring 180 on control arm 177 to hold lever 211 in any setting to which it is adjusted by handle 75 by friction with the curved rear face of segment 199 of wall 74. Lever 211 has pivoted to it a short straight arm 214 by pivot screw 215 in the side of lever 211 near its lower edge. The upper end of arm 214 has pivoted to it a lever 216 comprising a first arm 217 having a shorter arm 218 joined to it at an angle of about 150 degrees so that the lever has the general shape of a flat V turned upside down. Lever 216 is pivoted on arm 214 by screw 221 at the apex of the V. The longer arm 217 extends back to a position against the end of cross head arm 200 (Fig. 3). The end portion of arm 217 is longitudinally slotted at 219 and a pivot screw 220 on the end of arm 209 extends through slot 219. Referring again to Figs. 13 and 14 the shorter arm 218 of lever 216 extends downward and slightly forward and carries at its end a pivot screw 222 on which is pivoted the forward end of percentage valve lifting lever 223.

Valve lifting lever 223 extends back over the top of Venturi casting 66 to a dome-shaped end 224 having a hole loosely receiving the top of stem 225 of percentage metering valve 62, the end 224 of the lever being held under an adjustable nut 227 threaded onto the top of the stem.

Lever 223 has a transverse ridge or fulcrum 228 on its lower edge which bears on the top face of casting 66 a short distance from valve stem 225 to afford a point of leverage for lever 223 and also has a hole adjacent the fulcrum loosely surrounding the body of guide pin 205 (see Fig. 18).

As is shown clearly in Fig. 8, valve stem 225 of the percentage metering valve 62 extends down into Venturi chamber 54 where it is provided with an enlarged conically tapered head 226 positioned to seat in the mouth of passage section 49d to close the valve. Stem 225 is slidably mounted at its upper end in screw plug 229 screwed into a threaded opening in the top wall of casting 66 leading to chamber 54. A helical compression spring 230 is disposed over stem 225 and held under compression between the shoulder formed by the base of valve head 226 and the inside face of plug 229, so as to press the conical head 226 of valve down into seating relationship with the mouth of passage section 49e. Lever 223 is arranged to oppose this spring by applying a lift to stem 225 through engagement with nut 227. Thus, by varying the tilt of lever 223 on its fulcrum 228 the valve can be opened by various amounts to vary the percentage of oxygen in the oxygen-air mixture fed to the venturi.

As already described, valve 62 provides a supply of oxygen to venturi 47 which is supplementary to that issuing through jet 46 (see Fig. 1). In addition, air can enter through opening 61 to mix with the oxygen. If valve 62 is widely opened, however, the oxygen supply to chamber 54 and venturi 47 will be sufficient to develop a slight excess of pressure in chamber 54 and thereby exclude entrance of air through openings 61, possibly with escape to the atmosphere of a slight amount of oxygen.

Since the rate at which oxygen issues from positive jet 46 is substantially constant regardless of the setting of speed control valve 56 which governs the rate of supply of gas or gas mixture to the patient it will be apparent that percentage valve 62 will require different settings to deliver the same percentage of oxygen to the patient with different settings of speed control valve 56. Thus, when valve 56 is nearly closed jet 46 may be able to supply sufficient oxygen to deliver 100% oxygen to the patient at this slow rate of breathing. However, when valve 56 is wide open percentage metering valve 62 will be needed to supplement jet 46 in order to keep up the oxygen percentage. The coupling of lever 216 with cross head arm 200, by pin 220, which controls speed control valve 56 makes it possible to maintain substantially the same percentage mixture regardless of the speed of flow to the patient by causing the opening of metering valve 62 to be increased and decreased in direct proportion to the increase or decrease in the opening of speed control valve 56.

Referring to Figs. 13 and 14, when crosshead arm 200 is lowered to close speed control valve 56 and shut off the supply of gas to the patient, lever 216 will be rotated in a counter-clockwise direction to bring lever arm 217 to a substantially horizontal position as shown in Fig. 13. This raises the forward end of valve lift lever 223 to tilt this lever on its fulcrum 228 and lower valve stem 225 to close valve 62 thus cutting off the oxygen flow through valve 62 as shown in Fig. 13. When crosshead arm 200 is raised to open valve 56 however, lever 223 will be tilted to lift valve stem 225 by an amount corresponding to the

amount that valve 56 is opened so that the oxygen supply keeps pace with the speed of supply to the patient. When valve 56 is wide open levers 216, 223 and valve 62 will be in the position indicated in Fig. 14.

The percentage of oxygen in the gas mixture supplied the patient can be varied by tilting lever 216 by handle 75. In Figs. 13 and 14 the handle is set at the position marked "100% oxygen" on the dial 184 (see Fig. 2.) It will be noted that arm 214 which is pivoted to segment lever 211 near its lower edge is of such length as to bring the path of movement of its upper end carrying pivot screw 221 directly over the end of shaft 174 on which lever 211 is also pivoted. When the speed control valve 56 is closed so that lever 216 is in the position shown in Fig. 13 pivot screw 221 will be directly in line with the end of shaft 174. If lever 211 is turned by handle 75 to the position shown in broken lines on Fig. 13 there will be no motion transmitted to valve 62, as the two pivots will be concentric. Valve 62 will therefore remain closed as long as speed control valve 56 is left closed.

When crosshead arm 200 is raised to open valve 56 arm 214 will be swung forward by lever 216 to bring pivot screw 221 forward of shaft i. e. to the right of it as viewed in Figs. 13 and 14. The degree of eccentricity of screw 221 will depend on the amount valve 56 is opened. With valve 56 wide open and handle 75 in the "100%" position as shown in solid lines in Figure 14 valve 62 will be open wide to supply the maximum quantity of oxygen to Venturi chamber 54. If handle 75 is rotated upward to another position, such as that shown in broken lines in Fig. 14, arm 214 will raise pivot pin 221 thereby raising lever 216 to tilt lever 223 and lower valve head 226 to partially or completely close valve 62. At the top of its stroke, corresponding to "40% oxygen" on the dial (see Fig. 2) lever 211 will completely close valve 62 so that the oxygen is all supplied by jet 46. At intermediate settings valve 62 will supply part of the oxygen to produce various percentage mixtures between 40% and 100% oxygen.

When valve 56 is opened to half speed the eccentricity of pivot screw 221 will be less so that valve 62 will be opened a lesser amount at the various settings of lever 211. The percentage of oxygen in the mixture produced in the venturi will be the same, however, as with the wide open setting of valve 56.

The length of arm 214 is equal to the length of arm 218 of lever 216 and when segment lever 211 is rotated upward to the "40% oxygen" position it will bring pivot screw 215 directly in line with pivot screw 222. Hence, in this setting of lever 211 arm 214 and lever 216 will swing about screw 215 as a pivot and valve 62 will remain closed regardless of any upward or downward travel of crosshead arm 200.

The joint control of oxygen percentage by handle 75 and by the crosshead arm 200 for valve 56 is effective both when the device is used as a resuscitator and as an inhalator.

Figs. 18 and 21 show the construction of a safety valve 231 which is provided for equalizing chamber 50 to protect the patient from receiving excessive, dangerous or uncomfortable gas pressures. This valve comprises a cover disc resting over an opening 232 in the top of casting 73 leading to chamber 50. The general position of covered disc 231 is shown in Fig. 5. Disc 231 is provided with an annular ridge 233 which rests

against the top face of the casting and a central projection 234 is provided on the back of the disc carrying a control pin 235 of smaller diameter. Pin 235 is received in an opening in the end of sheet metal arm 236. Arm 236 extends out to the right side of the device as viewed in Fig. 21 and is tiltably held at its mid-portion under the head of set screw 237 passing through a hole in the arm and screwed into casting 73. A small lug 238 is bent down from the outer end of arm 236 and the lower end of a coil tension spring 239 is hooked to this lug. The upper end of spring 239 is anchored under the head of screw 240 (see Fig. 4) in selector control arm 171, the screw being set in a portion of the arm which extends back of its pivot axis on shaft 174. Spring 239, by its tension, holds valve 231 seated over opening 232. Should the positive gas pressure in chamber 50 exceed the spring tension it will lift valve 231 sufficiently to relieve the excess pressure. An advantageous feature of the arrangement is that the release pressure of the safety valve is placed under control of the selector handle so that the safety valve is adjusted to open at different pressures for different settings of the pressure control. This is effected by the connection of spring 239 to control lever 171 so that the tension on the spring is changed when the setting of selector handle 76 is changed. In each setting the tension is adjusted to cause the safety valve to open at a positive gas pressure slightly in excess of the pressure which will cause diaphragm 53 to trip distributing valve 44 over to the negative phase. For example, when handle 76 is set for "Adult," the pressure required to trip distributing valve 44 may be equivalent to 4 ounces load on spring 239. In this setting the spring will be given a tension of 5 ounces, so that, if by accident the distributing valve fails to trip or for any other reason the pressure in chamber 50 exceeds the 5 ounce pull of spring 239, the safety valve will open to prevent excessive pressures on the patient. If handle 76 is moved up to set the pressure for an infant at 3 ounces, for instance, the rear end of lever 171 carrying screw 240 will be lowered sufficiently to reduce the tension on opening 239 to 4 ounces thereby lowering the upper limit of pressure which can be supplied to the infant's lungs to a safe value for the infant. If handle 76 is raised to the "Steady flow" position the tension on spring 239 will be further reduced to a very low value so that the steady flow of gas to the patient will never be high enough to cause discomfort.

Figure 17 shows one of the Venturi jets 45 or 46, both jets being similar in structure, and illustrates the improved construction of the jet whereby clogging of the jet is made practically impossible. The jet structure is formed of two parts, namely a nozzle 241 and a jet cap 242. The nozzle part is externally threaded and screws into a threaded opening 243 in casting 66 leading to the Venturi chamber in line with the axis of venturi 47. The threaded opening is at the end of a recess 244 extending in from one side of casting 66, a similar recess being provided for the opposite jet on the other side of the casting. Nozzle 241 is provided with a flange 245 at its rear end which seats against the end of recess 244 and the back of the flange is provided with a screw-driver slot 246 to enable ready insertion and removal of the nozzle. The passage through the nozzle comprises a jet opening 247 of relatively small diameter extending to the tip of the nozzle

merging with a passage section 248 of much larger diameter extending to the rear end of the nozzle. Jet cap 242 comprises a threaded portion 249 which screws into the threaded outer end of recess 244, and a head 250 which seats against the side face of casting 66. A cylindrical projection 251 extends from the inner end of threaded portion 249 into passage section 248. Projection 251 is slightly smaller in diameter than passage section 248 so that a narrow annular slit or crack 252 is formed between them, the width of which is less than the diameter of jet opening 247. This affords an effective non-clogging dirt catcher between supply passage 48c, which enters recess 244 between parts 241 and 242, and the jet opening. Any dirt collected around the edge of crack 252 can readily be cleaned out by removing cap 242. By way of example, crack 252 may be .002 inch wide to protect a jet opening .020 inch in diameter. Due to its circular length crack 252 will still afford adequate gas passage to supply the jet and is much more rugged in construction than a screen with openings of the same order of magnitude.

Air opening 61 in the bottom of Venturi chamber 54 extends through the bottom of casting 66 as is shown in Fig. 5 where it is protected by an air filter and silencer 253 screwed onto the bottom of casting 66. This comprises a shallow sheet metal cap 254 having an air opening 255 in its bottom and containing a mass of filter material 256 such as loosely packed felt to filter entering air and absorb the hissing sound of the jet when in operation. Filter material 256 is supported away from the bottom of cup 254 by a circular plate 257 of smaller diameter than the cup, to allow air to pass around the edge. Plate 257 is secured to the bottom of the cup by spacing rivets 258 and the entire filter assembly is secured against the bottom of casting 66 over opening 61 by screw 259 passing up through plate 257 and threaded into the head of bolt 82.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A resuscitator and inhalator device comprising a gas pressure regulator having an inlet passage adapted to be connected to a source of oxygen supply and a gas supply passage for conveying oxygen from said regulator at a regulated pressure, a distributing valve fed by said gas supply passage, a venturi and a first and second jet directed respectively into the ends of said venturi, said distributing valve alternately closing first and second jet supply passages leading to said first and second jets respectively, and a movable valve element having a first position for directing the gas from said valve to said first jet and a second position for directing the gas from said valve to said second jet, walls enclosing separate chambers one of each surrounding said first and second jets respectively, said first jet supply passage having another gas passage to the chamber surrounding said first jet and an adjustable valve in said passage, said chamber surrounding said first jet having an air opening therein leading to the atmosphere, a patient's gas supply equalizing chamber and a gas passage between said chamber surrounding said second jet and said equalizing chamber, an adjustable valve in said last mentioned passage, walls enclosing a gas chamber

communicating with said equalizing chamber, one of said walls being movable responsive to gas pressure variations in said gas chamber, and means coupling a control element for said distributing valve to said movable wall for actuation thereby to move said valve to said first position responsive to negative pressure in said gas chamber and to said second position responsive to positive pressure in said gas chamber, and gas administering passages communicating with said equalizing chamber.

2. A resuscitator device comprising a passage adapted to be connected to a source of gas supply, a gas chamber, a venturi having two jets fed alternately by said gas supply for creating positive and negative gas pressures in said gas chamber, passages from said venturi to said chamber, an outlet from said chamber, valve means arranged to have two positions, one position for opening the passages for supplying positive gas pressures from said venturi to said gas chamber and said outlet and a second position for opening the passages supplying negative gas pressures to said chamber and said outlet, one of the walls of said gas chamber being movable responsive to gas pressure variations in said gas chamber, and means coupling said valve means to said movable wall to shift said valve means to said first valve position responsive to inward movement of said wall to a first wall position and to said second valve position responsive to outward movement of said wall to a second wall position.

3. A resuscitator device comprising a passage adapted to be connected to a source of gas supply, a venturi having two jets fed alternately by said gas supply for creating positive and negative gas pressures in a gas chamber, an outlet from said chamber, valve means arranged to have two positions, one position for opening the passages for supplying positive gas pressures from said venturi to said gas chamber and said outlet and a second position opening the passages supplying negative gas pressure to said chamber and said outlet, one of the walls of said gas chamber being movable responsive to gas pressure variations in said gas chamber, and means coupling said valve means to said movable wall to shift said valve means to said first valve position responsive to inward movement of said wall to a first wall position and to said second valve position responsive to outward movement of said wall to a second wall position, and adjustable spring means for resisting the inward movement of said wall to said first wall position and the outward movement of said wall to said second position.

4. A resuscitator device as claimed in claim 3, in which said spring means comprises a spring and lever assembly coupled to said movable wall, the leverage applied by said wall to said spring during said inward movement being greater than the leverage during said outward movement whereby the negative gas pressure required to operate said valve is less than the positive gas pressure required.

5. A resuscitator device as claimed in claim 4, in which said spring means are adjustable to simultaneously vary both the positive and negative valve operating pressures.

6. A device for administering a gas to a patient comprising gas supply passages, a gas administering passage communicating with said supply passages, adjustable control means for varying the pressure of gas supplied to said gas administering passage, a safety valve on said gas administering passage, an adjustable spring hold-

ing said safety valve closed, means actuated by said control means for adjusting said spring whereby the release pressure of said safety valve is varied responsive to adjustment of said control means but always exceeds the gas pressure settings of said control means.

7. A resuscitator device for administering alternate positive and negative gas pressures to a patient comprising a passage adapted to be connected to a source of gas supply, a venturi having two jets fed alternately by said gas supply for creating positive and negative gas pressures in a gas chamber, an outlet in said chamber means communicating with said chamber, valve means arranged to have two positions, one for opening the passage for supplying positive gas pressures from said venturi to said gas chamber and outlet and a second position for opening the passage supplying negative gas pressure to said chamber and said outlet, one of the walls of said gas chamber being movable responsive to gas pressure variations in said gas chamber, and means coupling said valve means to said movable wall to shift said valve means to said first valve position responsive to inward movement of said wall to a first wall position and to said second valve position responsive to outward movement of said wall to a second wall position, spring means for resisting the inward movement of said wall to said first wall position and the outward movement of said wall to said second wall position, a safety valve on said gas chamber, and a common control member for varying the resistance of said spring means to movement of said wall and simultaneously varying the release pressure of said safety valve.

8. A resuscitator device comprising an inlet passage adapted to be connected to a source of gas supply, Venturi means including first and second jets for creating alternately positive and negative pressures with respect to atmospheric pressure in an outlet chamber, a distributing valve fed by said passage having first and second jet supply passages leading to said first and second jets, respectively, having a movable valve element disposed in a valve chamber and shiftable between a first position for closing said first passage and a second position for closing said second passage, means comprising a spring biased resilient lever attached to said valve element for resisting the opening of the closed valve passage in both positions of said movable valve element against the gas pressure in said valve chamber.

9. A resuscitator device as claimed in claim 8, in which a diaphragm is coupled to said movable valve element to shift said valve element between said first and second positions.

10. A resuscitator device as claimed in claim 9, in which said valve comprises a cylinder with said jet supply passages opening through the two ends thereof and said inlet passage opening through the side wall thereof, and said movable valve element is slidable in said cylinder and has seating surfaces on the two ends thereof for closing said jet supply passages.

11. A resuscitator device as claimed in claim 10, in which said resilient control element comprises a pivoted arm extending laterally into coupling engagement with said movable valve element.

12. A resuscitator device as claimed in claim 11, in which said movable valve element has a plurality of sliding faces engaging the wall of said cylinder and the material of said element

21

is spaced from said cylinder between said sliding faces to permit gas passage around said element.

13. A resuscitator device as claimed in claim 12, in which said movable valve element is substantially rectangular in shape and the corners of said element are provided with said sliding faces.

14. A resuscitator device comprising an inlet passage adapted to be connected to a source of gas supply, Venturi means including first and second jets for creating alternately positive and negative gas pressures in an outlet chamber, respectively, a distributing valve fed by said passage having first and second jet supply passages leading to said first and second jets, respectively, and a movable valve element disposed in a valve chamber and shiftable between a first position for closing said first passage and a second position for closing said second passage, means for maintaining the gas pressure in said valve chamber to resist the opening of the closed valve passage in both positions of said movable valve element, a gas chamber, gas passages between said Venturi means and said gas chamber for supplying said gas chamber alternately with positive and negative gas pressures, one of the walls of said gas chamber being movable, a control arm

22

coupling said movable valve element to said movable wall for actuation thereby, to shift said movable element from said first to said second position responsive to negative gas pressures in said gas chamber and from said second to said first position responsive to positive gas pressures in said gas chamber.

15. A resuscitator device as claimed in claim 14, in which said valve comprises a cylinder with said jet supply passages opening through the two ends thereof and said inlet passage opening through the side wall thereof, and said movable valve element is slideable in said cylinder and has seating surfaces on the two ends thereof for closing said jet supply passages.
